COPYING SOUND EVENTS TAKEN IN AMPLITUDE RECORDS

Gustav Fries, Berlin-Charlottenburg, Germany;
vested in the Alien Property Custodian

Application March 12, 1941, Serial No. 383,059
In Germany February 10, 1940

3 Claims. (Cl. 101—401.1)

The present invention relates to a method of copying sound records of the amplitude type. More particularly the invention relates to a method of copying very long coherent sound records which with the aid of a needle or a luminous sound have been recorded upon a sound carrier as transverse vibrations, i. e., in amplitude or indented records. As a rule, a film strip is used as sound carrier.

It is well known to engrave on a strip-like sound carrier acoustic events in the form of grooves by means of a cutting needle and to closely fill the strips with such grooves. By means of such sound strips acoustic events of nearly any desired duration may be recorded and reproduced. With a length of strip of, for instance, 100 m. having 100 grooves upon each side, the duration of play is about 12 hours, provided the cutting or scanning speed amounts to 45.6 cm. per second. The nature of the strip as well as the density and the arrangement of the grooves on both sides render the copying of the strip rather difficult. Some copying methods cannot be used at all particularly the very advantageous optical methods. These and other reasons have heretofore made the copying of such strips practically impossible, particularly strips of this length, as often as is desired.

Moreover, it is also well known to produce by means of luminous signals upon one side of a strip-like sound carrier several sound traces side by side in transverse signals. Such sound traces, recorded with luminous sound, have already been treated in a manner similar to that of a light copying method by changing these traces into a gelatin swelling relief, producing therefrom intermediate galvanos and then using these for copying the original sound carrier. In another connection finally it is known to change by means of etching a luminous sound record into a needle sound record by recording the luminous sound in transverse signals in a trace the brightness of which changed from the middle line to the margins so that on etching of the trace recorded with luminous sound an elevated or deepened reproduction of the differently lighted portion was obtained which either directly resulted in a needle sound trace or during copying could be changed into such a sound trace.

The present invention, however, solves with the use of simple means the problem of directly producing from an original record a matrix that can be used without the original, for the purpose of copying, that is prepared mechanically, by electrolysis or in any other manner and par-

ticularly without subjecting the original sound strip to the action of a chemical bath. By this method a practically unlimited number of copies of greatest exactness can be made without any danger of wear. If desired, the new method may be carried out fully or semi-automatically.

A better understanding of this invention can be had from the following detailed description when considered with the drawings in which:

10 Figures 1 and 2 diagrammatically show fundamental details;

Figure 3 diagrammatically shows a portion of the device within which the copper strip serving as matrix is cleaned;

15 Figure 4 diagrammatically shows the device for drying the strip and applying the copying layer, and, moreover, illustrates the copying and developing of the copying layer;

Figure 5 diagrammatically shows the means for effecting etching and rinsing of the copper strip;

20 Figure 6 illustrates five sections, A, B, C, D, and E, through the strip indicating the individual phases of the production of the copper strip matrix;

25 Figure 7 diagrammatically represents the impressing of the matrices into the film material;

Figure 8 shows two sections, F and G, through the strips showing the operation before and after the impressing respectively;

30 Figure 9 diagrammatically shows the arrangement for impressing both sides of a strip the two ends of which are later on stuck together to form an endless reel;

Figure 10 diagrammatically shows the point of connection of the copper matrices shown in Figure 9; and

35 Figure 11 diagrammatically shows the register of the point of sticking together the ends of the strip.

40 The new copying method begins with sound events recorded in transverse signals the width of the trace of which shows differences in brightness. These differences of brightness may be due to a differently strong exposure of the luminous sound trace or to a different thickness of the strip over the width of the needle sound trace. The new copying method consists in producing from the record, for instance, photochemically a print form, or an intaglio form, refraining from

45 effecting prints from these forms but preparing by impressing a copy or a plurality of copies capable of being scanned by a needle. For the purpose of the invention the knowledge is of importance that in all printing methods, operating 50 without a screen, differences in brightness must

be changed to differences in the height of the print form and therefore the method and the means for carrying out the method must be developed as accurately as possible. For the purpose of the instant invention these differences in height are satisfactory and impressions are made with the aid of same.

The invention shall now be described by means of a luminous sound record as an example. First of all the original record is made which may be obtained by a light beam falling in point or gap form upon a light sensitive film strip and being controlled by the sound frequency in such a manner that a wave line in the manner of the Berliner record (amplitude or transverse record) is produced as in connection with a disc record, however, with different brightness in the width of the trace. After an ordinary development, the record appears as a wave line the width of which varies in darkness, whereas the part of the film strip not subjected to the light remains transparent. To obtain a definite profile of the material between adjacent grooves upon the matrix it is of particular importance that the light gap changes from the middle towards both sides in the manner of a gray wedge.

This gray wedge-like change of brightness may be decreasing or increasing from the middle of the strip outwards. The middle of the strip, therefore may be the darkest or the brightest portion. The latter particularly simple case is shown in Fig. 1.

The invention, moreover, consists in the knowledge that it is of no importance for the transfer of the intaglio method, known in the printing art upon the copy of sound films, whether the original record had been made with the aid of luminous signals or by means of a needle sound. The transverse luminous record and the needle record are equivalent for the new method and, therefore, may be replaced one for the other whenever desired. The examination of a needle sound record by means of light rays also results in a record strip the brightness of which changes from the middle line towards the margins. In the sense of the invention both kinds of record, therefore, photo-chemically allow the production of a metallic printing form having sound records in relief, i. e., the production of metallic forms which may be used for the direct production of a large number of very exactly impressed copies.

After these explanations a short hint only is required for the average expert to understand that the reproduced needle sound copies may be changed to a strip-like transverse record extending upon the surface of the carrier and capable of being scanned by luminous sound by means of a simple further step in the method, i. e., by means of a light copying process. Finally, it is clearly to be seen that in copying in accordance with the new method, the original sound strip is subjected to light rays only and is in no manner chemically or otherwise changed.

In the drawings the means for carrying out two of the various possible methods are shown according to which the originally produced film may be recorded as a light strip the width of which is of different brightness.

Fig. 1 diagrammatically shows the production of a matrix, II is the negative of I. By means of this negative the pigment paper III is exposed. The light rays, indicated by arrows, enter the uncovered portions of the negative, more or less penetrate the chromium gelatin

layer in dependence on the blackening of the negative and effect a reduction of the water solubility of said layer. The exposed pigment paper band III is transferred to the copper strip V and then rinsed with water. The portion of the gelatin layer which remains soluble is washed away, whereas the exposed portion is retained as groove relief, because it is hardened by the exposure. The etching of the copper

strip with a solution of iron chloride dissolves the copper first at such points at which the copper strip is most weakly covered by the gelatin relief, whereas the etching solution slowly penetrates the swelling gelatin and the etching occurs later on. In this manner the groove relief with all its finesses is transferred upon the copper strip. After etching, rinsing of the copper strip is effected and the copper strip matrix is finished.

As may be seen from Fig. 1 the method beginning with taking the record and ending with the finished matrix consists of five operations. One of these operations may be omitted, if the original exposure I is made upon a photographic reversal film, because then the production of the negative II is rendered superfluous.

The exposure may also be effected without the use of a gray wedge. In this case the etching would be effected in accordance with the line etching method by which the material between the grooves is profiled by means of repeated colorings and etchings with differently strong etching solutions.

For the manufacture of sound films on a factory scale a particular advantage of this step of the method according to the instant invention consists in this that in spite of the fact, that the copy is to be scanned by a needle guided in the sound groove, the needle is dispensed with on taking the record because the needle is rendered blunt by taking records extending over several hours, and that, moreover, due to the needle being dispensed with no chippings are produced. Consequently also the unavoidable inexactnesses and uncleannesses are dispensed with which accompany any finishing based upon removal of chippings in contradistinction to deforming operations.

Should it be desired for special purposes to listen to a record at once, this may be effected by means of a cutting needle. Hereby one side of the sound carrier which also may be a disc record is provided with a thin black layer (shown in Fig. 2 at I). Or for reproducing purposes the record is copied upon a photographic film so that for the exposure of the matrix the sound groove is bright. To effect the exposure the record I is brought upon the copper strip III provided with the copying layer II. After the exposure the development, rinsing and etching is effected. Hereby it is to be considered a favorable circumstance that by the profile of the cut groove the light permeability of the sound carrier, now transparent at this point, is as good as if the gray wedge increasing in darkness from the middle towards both sides would have acted in the same manner as during taking the record with light gap.

If the record in form of grooves has been made upon a strip which has no black covering or coating the latter may be applied after taking the record, as the color, for instance by rolling, covers the surface of the strip only, whereas the grooves, due to their depth, being left free.

In each case an intermediate negative of the record is used as copy which negative has been

produced as printing form for instance photochemically by means known in the printing art. Each method may be used which results in printing forms in relief which are practically free of screens and mechanically of sufficient strength and the margins of which are particularly exact.

Figs. 3-7 show by way of example a construction adapted for carrying out, with photochemical means, the entire novel copying method. As the number of copies is very large there may also be the question of a reproduction method. The entire device is represented in subdivided portions in Figs. 3, 4, 5 and 6. This device in a coherent operation allows the production of copies of sound records upon film strips which are scanned from the copy by means of a needle.

In carrying out the method according to the invention the fact is utilized that for instance chromium gelatin has the property of losing, depending on the magnitude of the entering amount of light, more or less its solubility in water under the action of this light. Chromium gelatin, therefore, is suitable as carrier for the sound copy of a sound recorded upon a film by means of light.

A mixture of fish-glue, distilled water, ammonium bichromate and ammonia for instance is suitable as copying layer.

The action is such that light rays falling into the layer more or less actively act upon the copying layer in accordance with the density of the film to be copied and in this manner effect a change of the water solubility of the layer. The change of the water solubility is the stronger, the deeper the light penetrates. At the most transparent points of the film to be copied, therefore, the change of the water solubility is largest and at the most covered points it is most weakened.

Wound upon the drum 1 is the metal strip, for instance a copper strip, serving as matrix which, as shown in Fig. 3, enters the tank 2 when unwound from said drum 1. In this tank the copper strip is cleaned by means of a swabber and a pulp of prepared chalk and a caustic alkali solution. In the tank 3 rinsing with water is effected which is supplied by a pipe 4 and discharged by a pipe 5. The tanks 6 and 7 also serve for cleaning purposes. The tank 6 preferably is filled with spirit such as alcohol and the tank 7 with a mixture of water and spirit. The drive for the feed of the copper strip 8 is effected by a motor 9 which also drives the swabber 10. The rollers 11 and 12 effect drying of the strip. A cross-section of the strip 8 taken along the line A-A in Figure 3 is shown at B in Figure 6.

The tank 13 contains the mass of the copying layer which, for instance, may be of the already mentioned composition and is applied at 14 upon the copper strip 8 in a thickness of about 0.2 mm. On the way to the copying lamp 16 the copying layer is dried and for this purpose a combined heating apparatus and centrifugal fan 15 is provided. A cross-section of the strip 8 with the copying layer applied thereto, taken along the line B-B in Figure 4, is shown at E in Figure 6.

As the strip 8 moves below the lamp 16, the film 25 to be copied is unwound from the drum 23 and guided between endless strips 17 and 18 by the rollers 19, 20, 21 and 22 and pressure is applied to the strip 8 provided with the copying layer 26. The transparent guide strip 18 hereby has the purpose of ensuring a good contact between the strip 25 provided in the example shown with four sound traces 34 and the strip 8. The

various strips and copying layer are shown in cross-section at C in Figure 6. This cross-sectional view was taken along the line C-C in Figure 4. After exposure by the lamp 16, the strip 25 is wound upon the drum 24, while the strip 8 carrying the copying layer 26 is developed in the tank 27 with water, supplied and discharged by pipes 28 and 29 respectively, by the fact that the portion of the copying layer 26 which remains water soluble due to the light rays not penetrating is rinsed away, whereas the water insoluble portion remains as webs between the grooves. A cross-sectional view of the strip 8 after emerging from the bath in tank 27, taken along the line D-D of Figure 5, is shown at D in Figure 6. Before the strip enters the etching bath in the tank 31, the lower side of same is covered at 32 with a fast drying acid proof layer of lacquer which prevents the etching liquid from attacking the lower side of the copper strip 8.

The etching operation is such that the etching liquid, in the method described, by way of example, a solution of iron chloride, first attacks and dissolves the copper strip covered with the groove relief formed by the copying mass remaining after development, at such points at which previously the light has most strongly impinged, and that the chloride dissolves the copper the deeper, the longer it acts. Practically, therefore, the groove relief from the copying mass is transferred to the copper strip, as the chloride is prevented from attacking the copper strip by the groove relief acting as protective layer.

In the tank 33 a last rinsing of the strip 8 with water is effected and then the copper strip matrix is finished. The sound grooves now remain upon the copper strip 8 as webs 34 in relief.

40 A cross-section of the strip after emerging from the bath in tank 33, taken along the line E-E, is shown at E in Figure 6. On further movement of the finished matrix 8 the latter reaches the device shown in Fig. 7.

45 Here the film strip 36, consisting of plexiglass, Cellophane or a similar material suitable as carrier for sound grooves to be provided with matrices and unwound from the drum 35 and eventually a second matrix 8a for impressing 50 the other side of the sound groove carrier 36 are supplied.

55 The two matrices 8 and 8a are moved towards each other and with the carrier 36 between same are, exactly guided by the guide members 37 and 37a, introduced between the rollers 38 and 39, between which the impression of the groove webs 34 in the groove carrier 36 is effected. To facilitate the impressing operation, the rollers 38 and 39 are heated and maintained hot. A cross-section 60 of the strips 8, 8a, and 36, taken along the line F-F in Figure 7, is shown at F-F in Figure 8. After the strips 8, 8a, and 36 have passed through the heated rollers 38 and 39, they appear as shown in the cross-sectional view G-G 65 of Figure 8, which was taken along the line G-G of Figure 7.

66 After effecting the impression, the now finished sound strip is wound upon the drum 40 and the matrices 8 and 8a are further moved to eventually effect further impressing.

The matrix may directly after or during the manufacture be listened to and this electromagnetically if the matrix is provided with reliefs, by scanning if the matrix has grooves by means 75 of which profiles in relief are impressed which

in turn are capable of being electromagnetically scanned. All the profiles may be scanned during the production and opposed upon frequency meters in such a manner that differences in the exactness of reproduction are noticeable at once optically or acoustically by means of a measuring indication.

The final positive, therefore, may obtain a deepened impression or an impression in relief. The impression in relief is by means of modern printing methods for the matrix easily be worked with such sharp or exactly formed edges from the surface of the sound carrier that the groove between the upper surface and the flank of the impression may be scanned by a needle, provided an indented record has been impressed. An intensity record in relief and also the above mentioned indented record in relief may, furthermore, be rendered conductive with the use of known means and may then electromagnetically be scanned.

In Figure 9 there is illustrated diagrammatically an arrangement for impressing both sides of a strip, the two ends of which are to be joined together to form an endless reel. Fragments of the strips H and J are shown in perspective in Figure 10. After the strip K has received impressions on both sides thereof, it is joined together as shown in perspective in Figure 11 to form the endless reel.

What I claim is:

1. The method of reproducing a sound record having a sound track thereon comprising cleaning the transverse surface of a moving metallic strip, depositing a layer of a light sensitive material on the cleaned surface of said moving strip as it moves from the cleaning treatment, the solubility of said light sensitive material being decreased on the exposure of said material to light, causing said strip after application of the light sensitive material thereon to pass in contact with a negative of the sound record to be reproduced while directing rays of light through said negative and onto the surface of said moving strip having said light sensitive material thereon, washing the moving strip and dissolving the soluble portions of the light sensitive material after the moving strip passes said negative

whereby to form a web and groove relief on the treated surface of the moving strip, etching the treated and washed surface of the moving strip following said washing step to transfer the web and groove relief to said surface, and then impressing the web and groove relief of said moving strip onto a film strip by causing said moving strip to pass adjacent to said film strip while pressing said moving strip into the film strip, said metal strip, negative, and film strip moving concurrently at a uniform speed.

2. The method as claimed in claim 1 wherein the etching step is carried out by the chemical action of an etching solution which will attack the metal of the moving strip.

3. The combination in a device for reproducing a sound record having a sound track of a movably supported metallic strip, drive means for moving said strip from end to end of said device, cleaning means through which said metallic strip passes arranged near one end of said device, means containing light sensitive material positioned forwardly of said cleaning means for depositing a layer of said material on a surface of said metallic strip, a light source arranged forwardly of said depositing means and adapted to direct light rays onto the surface of said metallic strip having the light sensitive material thereon, a negative of the sound record to be

reproduced being interposed between said light source and said metallic strip, means for supporting said negative and moving it while in contact with the metallic strip, developing means through which said metallic strip passes located forwardly of said negative and the light source, etching means through which the metallic strip passes positioned in front of said developing means, said etching means forming a groove and web relief on the treated surface of said metallic

strip, means movably supporting a film strip in contact with said metallic strip at a location between said etching means and the second end of the device, and means for pressing said etched metallic strip into said film strip, said metallic strip, negative, and film strip, moving concurrently at a uniform speed.

GUSTAV FRIES.
